UNITED STATES PATENT OFFICE

2,642,521

END CONNECTION FOR TUBULAR LAMPS

John William Easter, Acton, London, England,
assignor to Ozalid Company Limited, London,
England, a British company

Application May 17, 1950, Serial No. 162,551
In Great Britain May 26, 1949

3 Claims. (Cl. 240—11.4)

1

This invention relates to the external end connections and supports for electric lamps of the elongated tubular type (such for example as are used in association with the printing cylinder or "bend" of a photo-copying machine) comprising a transparent or translucent vitreous envelope at opposite ends of which leading-in wires, fused to the wall of the envelope, extend outwardly therefrom. In this type of lamp the envelope may contain a continuous filament, or in the case of a gas discharge lamp there may be an electrode at each end of an envelope containing a gas or vapour, a high voltage being applied across the electrodes to create an electrical discharge through the gas or vapour. In gas discharge lamps of the type described, the leading-in wires are usually protected by means of glass or porcelain beads threaded on the wires, but if the lamp is disturbed, there is a possibility of a leading-in wire protruding between adjacent beads and giving rise to a short circuit or injury to the operator. Moreover in lamps of the type described, considerable heat is generated when the lamp is in operation and hitherto the provision made for the consequent expansion of the vitreous envelope has not been entirely satisfactory.

One object of the present invention is to provide an external end connection and support for tubular lamps of the type described, wherein the risk of short circuiting is minimised.

Another object of the invention is to provide an external end connection and support for tubular lamps of the type described which in an improved manner may readily be coupled with and uncoupled from the source of electrical supply.

A further object of the invention is to provide an external end connection and support for tubular lamps of the type described in which, in an improved manner, the lamp is free to expand during operation.

According to this invention there is provided, for use in combination with an electric lamp of the type described having a transparent vitreous envelope at opposite ends of which leading-in wires, fused to the wall of the envelope, extend outwardly therefrom, an external end-connection and support for the lamp comprising an elongated tubular metal housing having one end part surrounding the body portion of the lamp at the end thereof and an opposite end part surrounding the corresponding leading-in wire, a ring-like circumferentially expandable clamp secured to the housing within the first-mentioned part thereof and shaped to surround and engage the vitreous envelope of the lamp providing for its free circumferential expansion during op-

2

eration, a sleeve of heat-resisting electrically-insulating material located within the second-mentioned part of the housing and providing an air-space enclosure within which the aforesaid leading-in wire is freely accommodated, and a plug-and-socket coupling comprising an insulating holder detachably connected to the second-mentioned part of the housing and a contact element carried by the holder and electrically connected to the leading-in wire aforesaid.

In one arrangement according to the invention the outside wall of the aforesaid part of the housing surrounding the leading-in wire is formed with a flat to which is attached, in a direction at right angles to the bore of the housing, the insulating holder which as aforesaid carries a contact element of the plug-and-socket coupling.

Preferably, the aforesaid part of the housing surrounding the leading-in wire is stepped down in diameter and eccentrically disposed in relation to the other part of the housing, an internal flange being formed at the junction between the two housing parts, and the aforesaid ring-like expandable clamp being secured to said flange.

The foregoing and other features of the invention are embodied in an example which will now be described with reference to the accompanying drawings, in which:

Figure 1 is an end view of the end connection and support for the lamp;

Figure 2 is a cross section at the line 2—2 of Figure 1;

Figure 3 is a cross section at the line 3—3 of Figure 2;

Figure 4 is a cross section at the line 4—4 of Figure 2; and

Figure 5 is a cross section, similar to Figure 2, showing an alternative method of attaching the plug-and-socket coupling to the housing.

Like reference numerals indicate like parts throughout the figures.

Referring in the first place to Figures 1 to 4, the illustrated device comprises an elongated tubular housing fabricated in light alloy and comprising two parts 10, 11, whereof the part 11 is stepped down in diameter and is eccentrically disposed in relation to the part 10 (as shown in Figure 2). The part 11 of the housing is formed with an integral longitudinal rib 12, slotted at 13, for the convenient attachment of the housing to the framework of the apparatus. At the position where the housing is stepped down in diameter, an annular rib 14 is formed, and to this rib there is attached, by means of screws 15, flanged arms 16 integral with a split cylindrical sleeve 17. The end of a gas discharge lamp

18 is supported by the split sleeve 17 at a position spaced inwardly from the leading-in wire 19 associated with that end of the lamp. An asbestos packing 20 is interposed between the sleeve 17 and the external wall of the lamp. Considerable heat is developed during operation of the lamp and the flexible mounting just described provides a satisfactory way of allowing for expansion of the lamp envelope.

Within the part 10 of the housing 10, 11, a metal bush 21 (conveniently of nickel) is located and held in place by means of a grub screw 22. The bush 21 is arranged to support a glass tube 23 enclosing the gas discharge lamp 18 and serving as a restriction filter for light rays having a harmful physiological effect. The end of the tube 23 is arranged to abut against a flange 24 on the bush 21, and the tube is further located by means of longitudinally extending strips 25 anchored by screws 26 to the end portion 10 of the housing and carrying pins 27 arranged to engage in apertures in the glass tube. In Figure 2—for convenience of illustration—a retaining strip 25 has been shown out of its proper angular setting.

Within the smaller diameter portion 11 of the housing a lining tube 28 of porcelain is located. The end of the lamp is arranged to extend (as shown in Figure 2) into the interior of the porcelain tube 28 through an opening 29. The end of the part 11 of the housing is closed by a plate 30 of fibrous insulating material secured to the housing by screws 31. The external wall of the part 11 of the housing is formed (as shown in Figure 4) with a flat area 32 at which there is secured to the housing an insulated holder 33 carrying one element, in the form of a split metal pin 34, of a plug-and-socket coupling. The holder 33 is located angularly by a spring pin 35 or similar device and is secured in place by means of a ring 36 which engages a flange 37 on the holder and which is secured to the housing by screws 38. The metal pin 34 is formed with a head 39 adapted to make a screw-threaded engagement with the insulated holder 33, a shoulder 40 on the pin being arranged to abut on an interior end wall of the holder. The head 39 of the pin extends into a short stub 41 arranged to project through an aperture 42 in the porcelain tube 28 and crimped to the end of the leading-in wire 19.

The socket member of the plug-and-socket coupling comprises a nickel core 50 to which is soldered the end of a cable 51. The core 50 is located within crimped and soldered to a plug 53 of fibrous insulating material and the free ends of the plug and core are surrounded by a hollow retaining cap 54 of fibrous insulated material secured by pins 55 to the plug 53. The pin holder 33 is formed (as shown in Figure 2) with a skirt 56, the external wall of which is screw-threaded for engagement by a metal nut 57 which has a flanged end 58 adapted to engage over the corresponding end of the retaining cap 54. By means of the nut 57 the plug-and-socket coupling may be securely held in the locked position, while by loosening of the nut, uncoupling is permitted. The cap 54 has a boss 59 which is arranged to surround the cable 51 at a position adjacent to the retaining cap 53. The cap 54 is split, one half 159 being removable and the two halves are held together by wire rings 160.

The foregoing arrangement provides for the dissipation of heat by the metal housing, the expansion of the lamp in use, the effective in-

sulation of the leading-in wire and the safe and ready disconnection of the device from the source of electrical supply.

The arrangement shown in Figure 5 provides for the attachment of the plug-and-socket coupling to the part 11 of the housing in a position in line with the housing. This attachment is effected by means of an angle fitting 60, 61, one arm 60 of which is arranged to be secured by screws 62 to the wall of the housing while the other arm 61 is arranged to encircle the flange 37' of the pin holder 33'. The arm 60 of the angle fitting carries an asbestos plug 63 arranged to fit into the opening in the wall of the housing and the adjacent opening 42 in the wall of the porcelain tube.

I claim:

1. For use in combination with an electric lamp of the type described having a transparent vitreous envelope at opposite ends of which leading-in wires, fused to the wall of the envelope, extend outwardly therefrom, an external end-connection and support for the lamp comprising an elongated tubular metal housing having one end 20 part surrounding the body portion of the lamp at the end thereof and an opposite end part surrounding the corresponding leading-in wire, a ring-like circumferentially expansible clamp secured to the housing within the first-mentioned 25 part thereof and shaped to surround and engage the vitreous envelope of the lamp providing for its free circumferential expansion during operation, a sleeve of heat-resisting electrically-insulating material located within the second-30 mentioned part of the housing and providing an air-space enclosure within which the aforesaid leading-in wire is freely accommodated, and a plug-and-socket coupling comprising an insulated holder detachably connected to the second-mentioned part of the housing and a contact element carried by the holder and electrically connected to the leading-in wire aforesaid.
2. An external end connection and lamp support as claimed in claim 1 in which the outside 45 wall of the aforesaid part of the housing surrounding the leading-in wire is formed with a flat to which is attached, in a direction at right angles to the bore of the housing, the insulated holder which as aforesaid carries a contact element of the plug-and-socket coupling.
3. An external end connection and lamp support as claimed in claim 1 in which the aforesaid part of the housing surrounding the leading-in wire is stepped down in diameter and eccentrically disposed in relation to the other part of the housing, an internal flange being formed at the junction between the two housing parts, and the aforesaid ring-like expansible clamp being secured to said flange.

60

JOHN WILLIAM EASTER.
